UNITED STATES PATENT OFFICE.

FREDERICK J. MACNISH, OF OAK PARK, ILLINOIS, ASSIGNOR TO THE CREAMERY PACKAGE MFG. COMPANY, OF CHICAGO, ILLINOIS, A CORPORATION OF ILLINOIS.

ROTARY PUMP.

No. 884,747.

Specification of Letters Patent. Patented April 14, 1898.

Application filed December 2, 1904. Serial No. 235,224.

To all whom it may concern:

Be it known that I, FREDERICK J. MACNISH, a citizen of the United States, residing at Oak Park, Cook county, Illinois, have invented a certain new, useful, and improved 5 Rotary Pump, of which the following is a full, clear, and exact description, such as will enable others skilled in the art to which it appertains to make and use the same.

10 My invention relates to rotary pumps and relates particularly to rotary pumps of that class which are used in dairies and creameries and milk stations for elevating milk and cream. It is necessary that such a pump 15 shall be cleaned thoroughly after being used, otherwise the pump becoming clogged and fouled with sour and putrid milk will cause the contamination of the next lot or quantity of fluid which is passed through it. This requirement makes it necessary that the pump 20 shall be of a kind to be quickly dismembered and cleaned. At the same time, the market value of such pumps is not great, and they must be so designed as to admit of their being made cheaply.

25 In the effort to meet all requirements as to operation, sanitation and cost, I find, speaking generally, that durability and efficiency have been sacrificed and with a view to correcting these faults, the object of this invention 30 is to provide a rotary pump that shall be efficient and durable, and yet of low cost and one which may be taken apart and put together by any person whether a mechanic 35 or not.

One of the chief objections to pumps of the old patterns lies in the fact that the inlet and outlet ports have been of irregular forms and difficult to clean, and a particular 40 object of this invention is to provide a so-called sanitary, or take-down pump which shall have direct, straight ports and passages formed in the pump cylinder instead of in the cylinder head as heretofore, so that when 45 clear water or a washing fluid is pumped through the cylinder and ports, both will be effectually cleared of objectionable accumulations, leaving only the wiping of the separable parts to be done.

50 A further object is to provide a pump from which the rotary piston may be quickly removed without recourse to bolts or screws.

A further and special object is to provide a sanitary pump whereof the cylinder shall be

a permanent, stationary part, while the rotary portion shall be removable.

Other objects of the invention will appear hereinafter.

My invention consists in the rotary pump 60 hereinafter described, as comprising a cylinder equipped with a swinging member for receiving one or both cylinder heads in place, in combination with suitable heads adapted to be so secured and to be readily detached, a rotary piston or cam adapted to be removed 65 from the cylinder when one head has been taken off, and means for driving said piston, the cylinder being provided with inlet and outlet openings or ports; and my invention consists further in various details of construction and in combinations of parts, all as hereinafter described and particularly pointed out in the claims appended to this specification.

My invention will be more readily understood by reference to the accompanying drawings, forming a part of this specification, wherein like reference numerals indicate like parts throughout, and in which

Figure 1 is a perspective view of a rotary 80 pump embodying my invention; Fig. 2 is a longitudinal vertical section thereof, Fig. 3 is a transverse vertical section on the line x—x of Fig. 2, Fig. 4 is a perspective view, showing the rotary piston of the pump and the 85 means for coupling the same to the driving shaft; Fig. 5 is a longitudinal section of the rotary piston, and Fig. 6 is a perspective view of the piston slides.

In the drawings, 2, represents a pyramidal 90 base, provided with a deep recess, 3, in its top and at one side having a bearing, 4, and at the other a bearing, 5, containing a stuffing box, 6. The pump driving shaft, 7, is arranged in these bearings and passes through 95 the stuffing box, 6. The recess, or notch, 3, serves to admit the gland of the stuffing box and also permits the adjustment thereof. The shaft is provided with fixed and loose 100 pulleys, 8 and 9, for a driving belt, and 10 represents a belt shifter. This shifter is slidable in the end of the arm, 11, which latter is fastened around the bearing, 4, by set screw 11'. If desired, the fixed and loose pulleys may be replaced by a water, steam 105 or electric motor. The pyramidal base is enlarged to form the cylinder head, 12, which is integral with the base.

The head, 12, is eccentric with relation to the shaft, 7, but is provided with two cylindrical recesses, 13 and 14, which are concentric with said shaft to receive the end and the boss, 15, of the rotary piston, 16. The pump cylinder, 17, is eccentric with respect to the shaft 7, and the rotary piston, 16, and is preferably integral with the head, 12, and the base, 2, although the cylinder may be detachable from the head, 12. The cylinder need not be removed from the base for the purpose of cleaning the pump and I therefore prefer to permanently attach it to the head, 12. The outer end of the cylinder is closed by a head, 18, having recesses, 19 and 20, for the end of the cylindrical piston, 16, and the stud, 21, thereon respectively. The stud, 21, is concentric with the piston, 16, and hence coaxial with the shaft, 7. The head, 18, and the end of the cylinder, 17, are provided with pins and pin holes, 22-23, to prevent the rotation of the head, 18, and secure it in proper position. The cylinder, 17, has two integral lugs, 24, and 25 represents a swinging bail that is pivoted on the lugs 24, and carries a hand screw, 26, which latter being forced against the head, 18, tightens it against the end of the cylinder. The bail, 25, is made of malleable or wrought metal, and its ends are bent inwardly over the studs, 24. By making the bail in this way, I avoid the use of removable studs on the cylinder, and the bail is made a permanent part of the structure so that it cannot be lost in shipment or in use. The inner end of the rotary piston is provided with a polygonal recess and is coupled to the driving shaft, 7, by a polygonal nut, 28, screwed upon the end of the shaft, 7, and loosely fitting the recess in the piston, 16. This coupling is sufficiently flexible to compensate for any slight disalignment of the parts and at the same time possesses the advantages of strength, simplicity and low cost. Furthermore, the coupling is such that the piston 45 when inserted in the cylinder may be very easily connected to the shaft.

The rotary piston, 16, contains a diametrical slot, 29, the length of which is less than the length of the piston, and equal to the distance between the inner surfaces of the cylinder heads. This slot is occupied by the slides, 30 and 31, which are thrust apart by springs, 32, arranged between them, so that the outer edges of the slides are always in contact with the inner walls of the cylinder. It is obvious that when the piston, 16, is rotated, the slides will be caused to move back and forth through the piston, because of the latter's eccentric position within the cylinder. The length of the slides is equal to the internal length of the cylinder, and the slides therefore, complete the rotary piston. The sides of the cylinder are provided with the integral pipe connections or bosses, 33 and 34,

serving respectively as the inlet and exhaust connections of the pump. The actual inlet opening, 33', may be of the full internal diameter of the boss, 33, but for the outlet or exhaust opening, I prefer an elongated slot, 34', communicating with the boss, 34, as shown in Fig. 3, and in dotted lines in Fig. 2. The operation of the pump as a means of propelling liquid is identical with that of other rotary pumps of the same type and does not require special description, but the operation or manipulation of the pump, considered from the standpoint of cleansability, differs from that of all others, inasmuch as to separate and remove the rotary piston it is only necessary to loosen the handscrew, 26, and swing back the bail, 25, whereupon the head, 18, and the piston, 16, may be taken from the cylinder. When this has been done, every part of the pump is found to be readily accessible, and may be easily, quickly and thoroughly cleansed. Although not a requisite for some uses, I usually provide my pump with a priming cup, 35, as shown in Fig. 3.

It is obvious that numerous modifications of my invention will readily suggest themselves to one skilled in the art and I do not therefore confine the invention to the specific constructions herein shown and described.

Having thus described my invention, I claim as new, and desire to secure by Letters Patent:

1. A rotary pump comprising a base, in combination with a horizontal shaft mounted in said base, a cylinder head and cylinder integral with said base and eccentric to said shaft, inlet and outlet connections communicating with the cylinder through ports in opposite sides thereof, a detachable cylinder head concentric with said cylinder, a rotary piston having its ends rotatably held in said heads, means loosely connecting said piston to said shaft for rotation thereby and means for securing said detachable head in place upon the cylinder, substantially as described.

2. A rotary pump comprising a base, in combination with a horizontal shaft mounted in said base, a cylinder head and a cylinder integral with said base, inlet and outlet connections communicating with the cylinder through ports in opposite sides thereof, a detachable cylinder head, a swinging bail and screw holding said detachable head in place, said cylinder heads having recesses which are concentric with said shaft, a rotary piston arranged within the cylinder and having its ends within said recesses, suitable center bearings upon the ends of said rotary piston, the inner end of said piston being provided with a polygonal recess, the end of said shaft being threaded and shouldered and a polygonal nut thereon forming a loose connection between said shaft and said piston, substantially as described.

3. A rotary pump comprising a base, 2, an integral cylinder head, 12, an integral cylinder, 17, integral bearings, 4 and 5, and integral inlet and outlet connections, 33 and 34, in opposite sides of the cylinder, in combination with a shaft, 7, held in said bearings, a detachable cylinder head, 18, a swinging bail and screw securing said head in place, said cylinder being eccentric with respect to 10 said shaft, said cylinder heads containing recesses which are coaxial with said shaft, a rotary piston having suitable vanes and held in said recesses and means forming a loose connection between the abutting ends of said 15 shaft and piston, as and for the purpose specified.

4. A rotary pump comprising a suitably supported cylinder having integral inlet and outlet connections upon its sides and integral

trunnions or lugs upon its top and bottom, in 20 combination with heads for said cylinder, the head adjacent to said trunnions being detachable, a malleable bail pivoted on said trunnions, a screw in said bail for fastening the detachable head, a rotary piston eccentrically arranged within the cylinder and held by the heads thereof and a shaft having its end loosely connected with said rotary piston, substantially as described.

In testimony whereof, witness my hand this 30 29 day of November, 1904, at Chicago, Cook county, Illinois, in the presence of two witnesses.

FREDERICK J. MACNISH.
